(57) **CLAIM**

I claim the ornamental design for a film applicator, as shown and described.

DESCRIPTION

FIG. 1 is a top, front and right side perspective view of a film applicator showing my new design;

FIG. 2 is a bottom, rear and left side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a front and right side perspective view thereof, shown in condition of use with the film applicator coupled with a cover body disclosed in broken lines to illustrate an environment;

FIG. 10 is a front and right side perspective view thereof, shown in a closed configuration;

FIG. 11 is a front and left side perspective view thereof, shown in condition of use with the film applicator coupled with an inner part disclosed in broken lines to illustrate an environment;

FIG. 12 is a front and left side perspective view thereof, shown in an alternate configuration;

FIG. 13 is a front and left side perspective view thereof, shown in a second alternate configuration;

FIG. 14 is a front and left side perspective view thereof, shown in condition of use with a cover body and an inner part disclosed in broken lines to illustrate an environment;

FIG. 15 is a front and left side perspective view thereof, shown in condition of use with a screen protector film disclosed in broken lines to illustrate an environment; and, FIG. 16 is a front and left side perspective view thereof, shown in a closed configuration.

The broken lines depict portions of the film applicator in which the design is embodied that form no part of the claimed design. The broken lines showing a cover body, inner part, and a screen protector film in FIGS. 9-16 represent environmental structure and form no part of the claimed design.
